UNITED STATES PATENT OFFICE

CHARLES MILLER, OF NEW YORK, N. Y.

DESIGN FOR A SHOE

Application filed February 5, 1932. Serial No. 42,750. Term of patent 3½ years.

To all whom it may concern:

Be it known that I, CHARLES MILLER, a citizen of the United States, residing at New York, in the county of New York and State of New York, have invented a new, original, and ornamental Design for a Shoe, of which the following is a specification, reference being had to the accompanying drawings, forming part thereof.

Figure 1 is a side elevational view of a shoe, showing my new design.

Figure 2 is a perspective view of a shoe, showing my new design.

A dominant feature of this design consists of providing the vamp and quarters with crossed lines of stitching. The lines also may be printed, embossed, serrated, punched, embroidered, or otherwise impressed upon the material but the design appearance will be substantially unchanged.

I claim:

The ornamental design for a shoe, as shown and described.

CHARLES MILLER.
